UNITED STATES PATENT OFFICE.

EDWARD R. HENRY, OF VANCEBORO, MAINE.

CLAMP OR VISE.

Application filed April 17, 1922, Serial No. 553,675. Renewed September 18, 1924.

To all whom it may concern:

Be it known that I, EDWARD R. HENRY, a subject of the King of England, residing at Vanceboro, in the county of Washington 5 and State of Maine, have invented certain new and useful Improvements in a Clamp or Vise; and I do hereby declare the following to be a full, clear, and exact description of the invention, such as will enable others 10 skilled in the art to which it appertains to make and use the same.

This invention relates to a clamp or vise.

It is primarily aimed to provide a novel 15 and efficient construction of clamp, vise or means designed to firmly hold the wheels of railway rolling stock to the rails while journal boxes are being jacked in order to repair or inspect hot boxes, so that the wheels will not elevate with the journal boxes, as 20 is frequently the case at present and which offsets the effect of jacking.

It is also aimed to provide the construction in such manner that it may be used 25 generally as a clamp or vise and for instance in connection with the repairing of laminated automobile bolster springs.

It is further aimed to provide a clamp of 30 the type mentioned having a stock provided with the fixed jaw, a screw associated with the stock and a movable jaw associated with the screw in cooperative relation with the fixed jaw.

Servient objects and advantages will 35 become apparent from a consideration of the description following taken in connection with accompanying drawings illustrating one practical embodiment.

In said drawings:—

Figure 1 is a front elevation of the im- 40 proved clamp;

Figure 2 is a plan view thereof;

Figure 3 is a vertical section through the clamp on the line 3—3 of Figure 1;

Figure 4 is a cross sectional view on the 45 line 4—4 of Figure 3 but through the entire device, showing the mounting of the lower jaw and

Figure 5 is a detail perspective view of the 50 upper jaw.

Like reference characters designate like or similar parts in the different views.

In reducing the invention to practice, a stock of any suitable shape or design is provided at 10, which is bored or recessed

centrally as at 11 and has a screw rod 12 55 loosely disposed therein. Rod 12 is of any length desired and has a thread at 13, preferably square in cross section, engaged by a thread 14 of a rotatable hand nut 15, disposed intermediate shoulders 16 of the stock so as 60 to prevent vertical displacement of the nut and which nut is insertable through an opening 17 provided through the stock.

The hand nut 15 may be engaged directly by the hand or if greater leverage is desired, 65 a rod or pin 18 may be disposed in any of a series of openings 19, provided in the hand nut and extending inwardly from the periphery thereof for that purpose. The rod 18 may have a knob 20 thereon to facilitate 70 manipulation and it may normally be disposed in a recess 21 provided in a reinforcing flange or extension 22 of the stock.

An upper or movable jaw is provided at 24 having a nut-shaped or other lug at 25, 75 provided with an opening 26 having screw threads therein to ride on the screw threads 13. Projecting from the jaw 24 is a lip 27, adapted to directly engage the work, for instance the inner surface of the flange of a car 80 wheel.

Attention is called to the fact that the type and specific design and construction of jaw 24 will vary according to the different wheels with which the same may be used, 85 or other work to be engaged thereby. Accordingly the illustration of movable jaw 24 is to be taken as conventional and merely as one example. It is however of a shape adapted for use both on freight car wheels 90 and passenger car wheels.

It will be noted that the work face of the lip 27 is preferably roughened or serrated as at 28. Also it will be seen that the lip is laterally enlarged as at 29 and may have a 95 reinforcing rib or flange 30 integral therewith.

A fixed or lower jaw is provided at 31 to coact with the jaw 24, in the case of a car wheel, being adjusted to engage the under surface of the tread flange of a rail, and with its engaging surface preferably roughened or serrated as at 32. The jaw 31 is secured to the stock 10, preferably extensibly 100 or adjustably. To this end, a plurality of studs 33 may extend from the jaw 31 and be slidably disposed in recesses 34 of the stock. One of the pins or studs 33 is pref-

erably slotted as at 35 and a fastening pin or screw 36 may be secured to the stock with its inner end disposed in the slot 35 an abutment for the shoulders or end walls 37 of the slot 35, to prevent detachment of the jaw 31 from the slot.

In addition to the flange 32, the stock may be further reinforced by flanges integral therewith as at 38.

10 In use, contemplating the fastening of a car wheel to a rail so that the car wheel will not be raised with a journal box while the latter is being jacked, the jaw 24 may be rotated on the rod 12 until it is at the desired distance from the jaw 31. Thereupon the lip 27 at its serrated edge 28 is placed in contact with the inner surface of the inner flange of the wheel and the serrated surface 32 of jaw 31 is placed in contact with the under surface of the tread flange of the rail. Thereupon the hand wheel 15 is operated in order to clamp the jaws to the work, being operated by direct engagement of the pin 18 in the recesses 19 and subsequent turning of the pin. It will be clear of course that the jaw 31 may be manually slid relatively to the stock 10 to accommodate it to the work, its sliding movement being limited by the pin 36.

30 As the application and use of the invention has been described with respect to means of one type, its application and operation with respect to other means will be apparent.

As merely one practical embodiment has been illustrated and described, it is to be understood that changes in the details may

be resorted to provided they fall within the spirit and scope of the invention.

I claim as my invention:—

1. A clamp having a stock, a jaw thereon, 40 a rotatable nut carried by said stock, a screw rod engageable by said nut, said screw rod securing the nut against displacement from the stock, and a jaw screw threaded on said rod to coact with the first mentioned jaw. 45

2. A clamp having a stock, a jaw thereon, a screw rod, a jaw on said screw rod to coact with the first mentioned jaw, a rotatable nut to actuate said screw rod, a rod detachably applicable to said nut to facilitate turning thereof, said stock having an extension integral with it provided with a recess, and said recess serving as a means to normally retain said screw rod. 50

3. A clamp having a stock provided with a jaw, said stock having an opening and means integral with the stock providing shoulders at said opening, a rotatable nut disposable intermediate said shoulders, a screw rod engaged by said nut, said screw rod retaining said nut in the stock against displacement, said stock having a bore to accommodate said rod, and a jaw screw threaded on said rod to coact with the first mentioned jaw. 55

In testimony whereof I affix my signature in presence of two witnesses.

EDWARD R. HENRY.

Witnesses:

G. BLAINE McKECHNIE,
PERCY E. JACKMAN.
